UNITED STATES PATENT OFFICE.

JOSEF GEIGER, OF AUGSBURG, GERMANY, ASSIGNOR TO MASCHINENFABRIK AUGSBURG-NUERNBERG, AKTIENGESELLSCHAFT, OF AUGSBURG, GERMANY, A CORPORATION OF GERMANY.

LOCOMOTIVE.

Application filed September 16, 1926, Serial No. 135,861, and in Germany September 23, 1925.

This invention relates to locomotives driven partly by Diesel cylinders acting directly upon the driving axle, and partly by compressed air cylinders also acting directly upon the driving axle and receiving compressed air from a compressor which is not connected to the driving axle but is operated from any suitable source of power. The pistons of the Diesel cylinders have to be of such large dimensions as compared with the pistons of the compressed air cylinders that considerable inertia forces are produced. This is due to the fact that, having regard to the available space, only a few Diesel cylinders (two or four at the most) can be arranged to actuate the driving axle, and to the fact that in order to obtain maximum efficiency from these cylinders they must be made double acting, so that consequently the pistons are operated upon from both sides. With these pistons the compensation or balancing of the masses gives rise to considerable difficulties.

Further difficulties also arise owing to the fact that favourable torque diagrams should be obtained not only for starting purposes, but also for normal continuous running. If for example in a four-cylinder locomotive, with two Diesel cylinders and two compressed air cylinders, the cranks were, as in the case of four cylinder steam locomotives, set at angles of 180° and 90°, then the torque diagram would be worse than that of the steam locomotive and consequently the starting tractive force in certain crank positions of the locomotive would be too low, whilst in other crank positions there would be the danger of slipping of the wheels owing to too high a starting power in comparison with the force of adhesion.

The object of the invention is to avoid these two drawbacks by arranging the cylinders having the heavier moving parts inside or between those having the lighter moving parts.

In order that the said invention may be clearly understood and readily carried into effect, the same will now be described more fully with reference to the accompanying drawings, in which:—

Figure 1 shows diagrammatically one constructional form of the invention.

Figure 2 is a diagram of the crank settings in the construction shown in Figure 1, and Figures 3 and 4 are views similar to Figures 1 and 2 illustrating a second construction.

In the constructional form shown in Figures 1 and 2 two double acting compressed air cylinders L_r and L_l and two double acting two cycle Diesel cylinders D_r and D_l are provided, the Diesel cylinders with the heavier moving parts being arranged on the inside, and the air cylinders with the lighter moving parts being arranged on the outside. The cranks appertaining to the two Diesel cylinders are, furthermore, set at an angle of 135° in relation to each other and the cranks appertaining to the two air cylinders are set at an angle of 45° in relation to each other, whilst the angle between the cranks appertaining to the right hand air cylinder L_r and the left hand Diesel cylinder D_l , as also between the cranks appertaining to the left-hand air cylinder L_l and the right-hand Diesel cylinder D_r , amounts to 90° in each case. This arrangement, without any additional weight in the reciprocating parts assuming the connecting rods to be of infinite length, results in the acceleration forces of the reciprocating parts of each Diesel cylinder being about two and a third times as great as those of each air cylinder and the distance of each air cylinder from the symmetrical axis A—A is approximately three times that of each Diesel cylinder. Under these circumstances a complete balancing of the masses for the inertia forces of the first order is obtained and furthermore the inertia forces of the second order, which arise from the influence of the finite length of the connecting rods and each of which change twice per revolution can be kept smaller than the inertia forces of the first and second order in steam locomotives. The same remarks apply to the moments of the inertia forces of the second order. It is, however, of special importance that the moments of the inertia forces of the first order which are the decisive factors for quiet or steady running of the locomotive, can be completely overcome. Together with these considerable advantages the result is, furthermore, attained that the torque diagram on starting, when the Diesel cylin-

ders are subjected to the action of compressed air, is uniform and only deviates from a straight line by about 10%. Under running conditions when the Diesel cylinders operate 5 on the Diesel principle, on the contrary, the so called tangential inertia forces act, in the neighborhood of the usual revolution speeds, in such a manner upon the torque diagram that this diagram is also uniform or approxi- 10 mately so. Finally as a further advantage of this arrangement it may be mentioned that the bearing pressures in the cranked driving axle are very slight due to the stated crank setting and the driving axle itself is stressed 15 comparatively slightly by bending loads originating from the piston forces.

All the above advantages are also attained to a certain extent if, for example, all four 20 cylinders are Diesel cylinders working at one side of the pistons according to the Diesel principle and, at the other side (cross-head side) on the compressed air method. The proportion of the inertia forces of the recip- 25 roating parts appertaining to the outer and inner cylinders must, in this case also, be in the proportion of approximately 1 to 2½ and the distances from the symmetrical axis 30 A—A must be 3 to 1.

In the arrangement shown in Figures 3 and 35 4, which is mainly intended for locomotives of low power and low speed, two Diesel cylinders D_r and D_l are arranged on the outside, whilst centrally between them there is pro- 40 vided a double acting compressed air cylinder L which has approximately the same effective volumetric capacity as the two Diesel cylinders together. The setting of the cranks appertaining to the three cylinders is 120°. In this arrangement the stresses upon the 45 driving axle are less than if the Diesel cylinder or cylinders were arranged inside. In contradistinction to the arrangement first described here there cannot be obtained a reduction or elimination of the moment of the 50 inertia forces of the first and second order, which however is not prejudicial having regard to the small dimensions of the moving parts and lower speed of the locomotive which are presupposed for this arrangement. The 55 compensation of the free forces of inertia of the first and second order is however practically complete just as in the constructional form described first.

The exact crank settings hereinbefore 60 mentioned are not to be regarded as strictly binding for the invention; crank settings which approach the figures set forth are to be considered as coming within the scope of this invention.

Having now particularly described and ascertained the nature of my said invention and in what manner the same is to be performed, I declare that what I claim is:

65 1. A locomotive driven by both Diesel and compressed-air-type engines acting directly

upon the same driving axle, an engine of one of the types having heavier moving parts being arranged between a pair of engines of the other type having lighter moving parts.

2. A locomotive driven by both Diesel and fluid-pressure engines acting directly upon the same driving axle, the connection between the axle and an engine of one of the types which has heavier moving parts being arranged between the connections to the axle of a pair of engines of the other type having lighter moving parts, the crank-shafts of all of the engines being angularly offset so that the inertia forces of the various reciprocating parts are effective in compensating one another and so that the starting torque at various angular positions of the driving axle is approximately uniform.

3. A locomotive driven by both Diesel and compressed-air-type engines acting directly upon the same driving axle, the connection between the axle and an engine of one of the types which has heavier moving parts being arranged between the connections to the axle of a pair of engines of the other type having lighter moving parts, the crank-shafts of adjacent engines being angularly offset with relation to one another by angles exceeding 90°.

4. A locomotive driven by both Diesel and fluid-pressure engines acting directly upon the same driving axle, there being two Diesel engines having their crank-shafts set at an angle of 135° to each other, arranged on the inside between two fluid-pressure-type engines having their crank-shafts set at an angle of 45° to each other, the cranks of alternate engines being set at 90° to each other.

5. A locomotive driven by both Diesel and compressed-air-type engines acting directly upon the same driving axle and arranged in alignment, there being two Diesel engines having their crank-shafts set at an angle of 135° to each other, arranged on the inside between two compressed-air engines having their crank-shafts set at an angle of 45° to each other, the cranks of alternate engines being set at 90° to each other, and the Diesel engines having heavier moving parts than the compressed-air-type engines.

6. A locomotive driven by both Diesel and compressed-air-type engines acting directly upon the same driving axle and arranged in alignment, there being two Diesel engines having their crank-shafts set at an angle of 135° to each other, arranged on the inside between two compressed-air engines having their crank-shafts set at an angle of 45° to each other, the cranks of alternate engines being set at 90° to each other, the compressed-air engines being connected to the axle at points about three times as far from the center of the axle as the connections between the adjacent Diesel engines and the axle.

7. A drive of the class described in which

a plurality of engines of different types and with moving parts of different weights are connected to a common driving axle, the various points of connection of the various engines being spaced along the axle from a zone of neutral stress amounts coordinated with the inertia force of the reciprocating parts

of the various engines so that the inertia forces of the various reciprocating parts are substantially balanced.

In testimony whereof I have affixed my signature.

JOSEF GEIGER.
